C. A. Snow, Esq.

UNITED STATES PATENT OFFICE.

HOUSTON S. BAKER, OF HOLLANDALE, MISSISSIPPI.

BACK-PEDALING BRAKE.

SPECIFICATION forming part of Letters Patent No. 643,450, dated February 13, 1900.

Application filed October 20, 1899. Serial No. 734,256. (No model.)

To all whom it may concern:

Be it known that I, HOUSTON S. BAKER, a citizen of the United States, residing at Hollandale, in the county of Washington and State of Mississippi, have invented a new and useful Back-Pedaling Brake, of which the following is a specification.

This invention relates to bicycles in general, and more particularly to the driving mechanism thereof, and it specifically relates to the brake mechanism which is operated from the cranks.

The object of the invention is to provide a construction in which as the pedals are moved forwardly they will have a driving action upon the crank-sprocket, when held stationary the crank-sprocket will run free, and when rotated rearwardly will act to apply the brake. These results are accomplished by means of a ratchet arrangement between the crank-sprocket and an adjacent crank, by means of which the cranks are fixed with respect to the sprocket when rotated in one direction, and through the medium of a brake-disk upon the crank-axle having a ratchet connection with the second crank, which acts to engage the disk with the crank when the latter is rotated rearwardly, the brake-disk having connection with a brake-block upon the rear-wheel hub.

In the drawings forming a portion of this specification and in which similar numerals of reference designate like and corresponding parts in the several views, Figure 1 is a side elevation showing the drive mechanism and the adjacent portions of the bicycle and illustrating the application of the brake and ratchet mechanisms. Fig. 2 is a detail perspective showing the crank-axle with the cranks, the crank-sprocket, and the brake-disk applied thereto. Fig. 3 is a detail perspective showing the brake-block. Fig. 4 is a detail section of the crank-sprocket, taken through one of the pawls. Fig. 5 is a view, partially in elevation and partially in section, showing means for adjusting the crank-sprocket upon the crank-shaft.

Referring now to the drawings, 5 represents the bottom bar, 6 the seat-tube, 7 a tie-rod, and 8 a rear-fork side of a bicycle-frame of the usual construction, the bottom bar and seat-tube being connected to the crank-hanger, together with the tie-rod, in the usual manner.

In the crank-hanger is journaled a crank-shaft 9, having cranks 10 fixed to its extremities, the rear ends of the cranks being squared, 55 as shown. A crank-sprocket 11 is mounted loosely upon the shaft 9 in the usual position and is in the form of a preferably flat disk, the adjacent crank 10 being bent inwardly at opposite sides of the crank-shaft in order to 60 lie close to the outer face of the sprocket, the rear end of one of said cranks adjacent the crank-sprocket being projected rearwardly beyond the crank-shaft, as shown in Fig. 2.

The crank-sprocket 11 carries a plurality of spring-pressed pawls 13, which are in the form of blocks movably disposed within and closely fitting slots 14 in the sprocket. The projecting ends of these blocks are cut away 70 to form a slant or incline 15 to permit the riding of the ends of the adjacent cranks thereupon when the crank is rotated rearwardly, these blocks being held yieldably in position through the medium of spring-plates 75 16, attached thereto and to the inner face of the sprocket, the plates projecting beyond the blocks to limit the outward movement of the latter. Any number of these pawls may be employed, and upon reference to Fig. 2 of the 80 drawings it will be seen that as the crank is moved forwardly it will engage the outwardly-extending straight sides of the pawls and will thus rotate the crank-sprocket, and as the crank is rotated rearwardly it will ride upon 85 the faces 15 of the pawls and will depress the latter to permit the crank passing thereover. Also if the crank be held stationary the crank-sprocket may run freely in a forward direction.

A brake-operating disk 17 is loosely disposed upon the crank-axle adjacent the crank 10 farthest from the sprocket 11, this disk having an opening similar to those in the sprocket 11. In this opening of the disk 17 95 is disposed a spring-pressed pawl 18, having the same construction and arrangement as the pawls in the sprocket 17. This pawl 18 projects into the path of the adjacent crank 10 to fixedly engage the latter when it is 100 moved rearwardly and to permit the crank passing freely thereover when moved forwardly. This brake-operating disk 17 has a connecting-rod 19 pivoted thereto, which

reaches rearwardly to a brake-block disposed upon the hub of the rear wheel. This brake-block is in the form of a pitman-head and comprises an inner end portion 20, having a perforation 21 for attachment of the rod 19, and an outer portion 22, connected with the portion 20 through the medium of the usual adjusting-bolts 23. The parts 20 and 22 are cut away at their adjacent edges to fit upon the hub of the rear wheel, which latter is provided with a brake-drum of the usual construction. When the pedals are moved rearwardly, the pawl 18 is engaged by the adjacent crank and acts to lock the brake-operating disk to the crank, so that the disk is moved rearwardly and draws the outer portion 22 against the brake-drum of the rear-wheel hub to stop the movement of the machine.

It will of course be understood that in practice a different construction and arrangement of pawl may be employed and that various other modifications may be made without departing from the spirit of the invention.

In order to clamp the sprocket 11 firmly against the portion 17, a sleeve 30 is mounted loosely upon the shaft 9, and engaging the exterior threads of this sleeve is a thumb-nut 31, having an inwardly-directed flange 32, which closely encircles the shaft. Thus by adjusting the nut 31 upon the sleeve the aggregate length of the nut and sleeve may be varied and the inner end of the nut may be caused to impinge against the end of the crank-hanger, while the outer end of the sleeve rests against the sprocket and may be caused to force it outwardly. A set-nut 33 holds the sleeve and nut in their proper adjusted positions. Also, as shown in Fig. 4 of the drawings, in order to prevent the noise of the spring-plate 16 striking against the adjacent sprockets there is placed a sheet of rubber 34 between the plate and the sprocket.

What is claimed is—

1. In a vehicle, the combination with a crank-axle and a drive-wheel, of a sprocket mounted loosely upon the crank-axle and having pawls mounted therein and projecting at right angles to the face thereof, a crank upon the crank-axle adapted to engage with said pawls in one direction and to pass over them in the opposite direction, connections between the crank-sprocket and the drive-wheel, a brake-disk mounted loosely upon the crank-axle and having a pawl projecting at right angles to the face thereof adapted for en-

gagement by the adjacent crank when moved in one direction and to permit free movement of said crank in the opposite direction, and a brake having connections with the brake-disk for operation thereby. 60

2. In a vehicle, the combination with a crank-axle and a drive-wheel carrying a brake-drum, of a sprocket upon the crank-axle and having openings therethrough, pawls disposed in the openings and projecting from the face of the sprocket at right angles thereto, a crank fixed to the crank-axle and adapted for engagement with the pawls to rotate the sprocket in one direction and to move freely over the pawls in the opposite direction, a sprocket upon the drive-wheel connected with the crank-sprocket, a brake-operating disk mounted loosely upon the crank-shaft, an opening in the disk, a pawl disposed in said opening, a crank fixed to the crank-shaft and adapted for engagement with the pawl of the disk when moved in a direction to cause free movement of the opposite crank over the crank-sprocket and to slide freely over the pawl in the opposite direction, a brake encircling the brake-drum, and connections between the brake and the disk for operating the brake. 70

3. In a vehicle, the combination with a crank-axle and a drive-wheel, of a crank-sprocket loose upon the axle and having openings therein, spring-pressed pawls mounted loosely in the openings, and adapted to project outwardly therethrough, a crank fixed to the crank-axle and adapted for engagement with the pawl when moved forwardly and to move freely over the pawl when moved rearwardly, a sprocket upon the drive-wheel having connections with the crank-sprocket, a disk mounted upon the crank-axle, an opening in said disk having a spring-pressed pawl disposed loosely therein, a crank fixed to the crank-axle and adapted to engage the pawl when moved rearwardly and to pass freely over the pawl when moved forwardly, a brake-drum upon the rear wheel, a brake disposed upon the drum, and connections between the brake and the disk for operating the brake. 85 90 95

In testimony that I claim the foregoing as my own I have hereto affixed my signature in the presence of two witnesses.

HOUSTON S. BAKER.
